UNITED STATES PATENT OFFICE.

GEORGE HIPWOOD, OF BOSTON, MASSACHUSETTS.

ARM-REST ATTACHMENT FOR CRUTCHES.

1,298,714.

Specification of Letters Patent.

Patented Apr. 1, 1919.

Application filed January 12, 1918, Serial No. 211,529. Renewed August 3, 1918. Serial No. 248,212.

To all whom it may concern:

Be it known that I, GEORGE HIPWOOD, a citizen of the United States, residing at Boston, county of Suffolk, State of Massachusetts, have invented an Improvement in Arm-Rest Attachments for Crutches, of which the following description, in connection with the accompanying drawing, is a specification, like characters on the drawing 10 representing like parts.

This invention relates to an arm rest attachment adapted to be applied to the head of an ordinary crutch, and it has for its object to provide a novel attachment of this 15 type which when applied to the crutch provides a yielding, resilient arm-supporting portion which adds greatly to the comfort of the user of the crutch.

Most crutches are provided with a wooden 20 head having an upper concave arm-supporting surface, and sometimes this crutch head is covered with cloth for the purpose of providing a softer surface. My improved attachment is constructed so that it can be 25 readily applied to any ordinary wooden crutch head, and when so applied it presents a flexible, longitudinally-resilient arm-supporting surface situated above the concave upper face of the crutch head so that the 30 weight of the person will be received on the flexible longitudinally-resilient arm-supporting portion of the attachment instead of on the crutch head, thereby adding greatly to the comfort of the user of the crutch.

In order to give an understanding of my 35 invention, I have illustrated in the drawings a selected embodiment thereof which will now be described, after which the novel features thereof will be pointed out in the 40 appended claims.

Figure 1 is a side view of a crutch head having my improved attachment applied thereto;

Fig. 2 is a top plan view;

Fig. 3 is an underside view of the left-hand end of Fig. 1;

Fig. 4 is a section on the line 4—4, Fig. 2;

Fig. 5 is a view similar to Fig. 1 showing the position of the parts when weight is applied to the attachment;

Fig. 6 is a perspective view of one of the clips or fastening devices.

1 indicates the wooden head or arm rest of an ordinary crutch which is provided with 55 a concave upper face 4, and 2 indicate the two side members of the crutch on which the

head 1 is supported. My improved crutch attachment comprises two fastening devices or clips which are adapted to be inserted over the ends 3 of the crutch head 1, and a flexible longitudinally-resilient arm-supporting member sustained by said fastening devices above the concave upper face 4 of the crutch head 1. The means for securing the arm-supporting member to the clips or fastening 60 devices is preferably so constructed that when downward pressure is applied to the central portion of the arm-supporting member, the ends thereof will be raised. The advantage of this is that the movement of 65 the arm-supporting member toward the head of the crutch is partially counteracted by the upward movement of the ends of the arm-supporting member so that said arm-supporting member will not be brought into contact with the central part of the crutch head, even when considerable weight is applied thereto. The clips or fastening devices, 70 which support the arm-supporting member and are adapted to be applied to the ends 3 of the crutch head, are indicated generally at 75 5. While these clips may be made in various ways without departing from the invention, the construction herein shown is one presenting two sides 7 and 8 connected by the portion 6, the sides 7 and 8 resting on the top and bottom of the end 3 of the crutch head and the portion 6 passing around the tip of the crutch head. The portion 7 is provided 80 with two arms 9 which extend around the 85 sides of the crutch head and which may be clamped firmly to the crutch head by means of a clamping screw 10. When the clamping screw 10 is loosened, each clip or fastening device may be readily withdrawn from 90 the end of the crutch head.

The arm-supporting member is indicated generally at 11 and it is secured at its ends to two levers 12 which are pivotally secured to the clips and extend upwardly therefrom. 100 The lever members 12 are shown as having two side portions 13 which are pivoted to opposite sides of the clip or fastening device at 14, the two sides 13 being connected by the bridge portion 15 to which the arm-supporting member 11 is fastened.

The arm-supporting portion 11 is flexible and is also made longitudinally resilient and while said member may be constructed in a variety of different ways without departing 110 from the invention, the construction and arrangement herein illustrated has many ad-

vantages. It consists of a member 18 of leather or some similar material which is reinforced by a plurality of helical springs 19 that are situated beneath the member 18. 5 These springs 19 are fastened at their ends to loop devices 20 and the member 18 is provided at each end with an elongated tab or strap 21 which is passed around the bridge 15 of one of the levers 12, thence through one 10 of the loops 20 and thence around the end of the crutch head, said tab passing between the two arms or sides 13 of the lever 12 and extending underneath the crutch head and being secured to a suitable hook or fastening 15 member 22. This fastening element 22 will preferably be formed on the clip 5, but might be carried directly by the crutch head. The end of the tab 21 will preferably have a plurality of apertures 23 therein through 20 any one of which the hook 22 may be inserted. By this construction the member 18 will be held taut by the resiliency of the springs 19 and the tension of the springs can be increased by drawing the tabs 21 tighter, 25 and can be decreased by letting out the tabs somewhat.

The lever members 12 are preferably acted upon by springs which tend to throw them outwardly away from each other. In the 30 construction shown there is one such spring shown at 17, said spring being in the form of a leaf spring fastened at one end to the end 6 of the clip, the other end 28 of the spring loosely passing through a guide 24 formed on the clip. These springs 17 have engagement with a loop portion 16 of the lever 12 and thereby tend to throw the outer ends of the levers outwardly. The application of weight or downward pressure to the 35 central portion of the arm-supporting member 11 will tend to swing the upper ends of the levers 12 inwardly, such movement being resisted and cushioned by the springs 17. Moreover, the downward pressure on the 40 arm-supporting member tends to elongate the springs 19 and the weight which is applied to the crutch will thus be resiliently sustained partially by the springs 17 and partially by the springs 19. Owing to the 45 fact that the levers 12 incline upwardly and outwardly from their pivots the swinging movement of the levers due to the application of weight to the arm-supporting member will elevate the outer ends and thus the 50 ends of the arm-supporting member are raised as the central part is depressed. The advantage of this is that the downward yielding movement of the arm-supporting member is partially counteracted by the 55 raising of the outer ends of the levers, and hence there will be no danger that the arm-supporting member will be depressed into contact with the crutch head 1 when in use.

60 65 The construction herein shown has the

further advantage that the tension of the springs 19 can be adjusted to suit the weight which is applied to the crutch. If the crutch is to be used for a person of light weight, the tabs 21 may be adjusted so as to give the 70 springs 19 less tension than if the crutch is to be used by a person of heavier weight. It is, of course, desirable that the flexible resilient arm-supporting member 11 should always be maintained out of contact with the 75 crutch head 1 while the crutch is being used, and this end can be accomplished by merely adjusting the resiliency of the springs 19 to correspond to the weight of the person who is using the crutch. 80

My improved attachment can be very easily applied to any crutch head and the shape of the clips or fastening devices 5 is such that they may be used on any ordinary crutch head. 85

I claim:

1. In a crutch attachment, the combination with two clip members adapted to be applied to the ends of a crutch head, of a lever pivoted to each clip member, and a 90 flexible arm-supporting member connecting the ends of the levers.
2. In a crutch attachment, the combination with two clip members adapted to be applied to the ends of a crutch head, of a 95 lever pivoted to each clip member, and a longitudinally-extensible arm-supporting member connecting the ends of the levers.
3. In a crutch attachment, the combination with two clip members adapted to be 100 applied to the ends of a crutch head, of a lever pivoted to each clip member, and a longitudinally-resilient arm-supporting member connecting the ends of the levers.
4. In a crutch attachment, the combination with two clip members adapted to be 105 applied to the ends of a crutch head, of a lever pivoted to each clip member, a longitudinally-resilient arm-supporting member connecting the ends of the levers, and means 110 for varying the resiliency of said arm-supporting member.
5. In a crutch attachment, the combination with two clip members adapted to be applied to the ends of a crutch head, of a 115 lever pivoted to each clip member, a flexible arm-supporting member connecting the ends of the lever, and a spring acting on each lever, said springs tending to swing the levers away from each other. 120
6. In a crutch attachment, the combination with two clip members adapted to be applied to the ends of a crutch head, of a longitudinally-resilient arm-supporting member, and means connecting the arm-supporting member to the clip members by which downward pressure applied to the central portion of the arm-supporting member will cause the ends thereof to be raised. 125
7. In a crutch attachment, the combina- 130

tion with clip members adapted to be applied to the ends of a crutch head, of a lever pivoted to each clip member, and an arm-supporting member comprising a flexible element, an extensible spring situated beneath said element, a loop at each end of the spring, each end of the flexible element passing around the upper end of the levers, thence through one of said loops, and thence 10 around the end of the crutch head, and means for adjustably anchoring the ends of said flexible element.

8. The combination with a crutch head, of two levers pivotally mounted thereon adjacent the ends thereof, each lever extend-

ing upwardly and outwardly from its pivot, and a flexible arm-supporting member connecting the ends of said levers.

9. The combination with a crutch head, of two levers pivotally mounted thereon adjacent the ends thereof, each lever extending upwardly and outwardly from its pivot, a flexible arm-supporting member connecting the ends of said levers, and springs acting on said levers and tending to hold said member taut. 20 25

In testimony whereof, I have signed my name to this specification.

GEORGE HIPWOOD.
